UNITED STATES PATENT OFFICE

NATHAN F. FRETTER, OF CLEVELAND HEIGHTS, OHIO

WICK CARRYING MEANS

Application filed August 18, 1930. Serial No. 475,932.

This invention relates to wick carrying mechanisms and more particularly to means for supporting and adjusting cylindrical wicks of the type used in oil stoves, lamps 5 and other oil-burning devices.

Heretofore the general practice has been to support such wicks within a perforated cylindrical sleeve, which surrounds the outer surface of the wick, and which is permanently secured to the wick by means of prongs 10 extending from the bottom of the sleeve and bent over to engage the interior of the wick. Generally these metallic sleeves extend upwardly to such an extent that they cover more than half of the outer surface of the wick, and thus, less than half of a wick 15 equipped with a sleeve of this type can be used, as the wick and sleeve must be thrown away as soon as the wick has burned down to the upper edge of the sleeve.

Accordingly, the general object of my invention is to provide a wick carrying mechanism in which nearly all of the wick can be burned before replacement is required.

20 A further object is to provide a wick carrier which can be easily replaced within the wick-carrier sleeve after the wick is used up.

Another object is to provide a wick-carrier sleeve which will not have to be replaced 25 whenever a new wick is inserted.

A further object is to provide a wick-carrier and a wick-carrier sleeve which lends itself readily to economical manufacturing methods, and which can be stamped out of a rectangular blank of sheet metal with few 30 operations and very little waste of material.

Other objects and advantages of my invention will appear from the following description of a preferred form thereof, reference 35 being made to the accompanying drawings. The essential characteristics are summarized in the claims.

In the drawings, Fig. 1 is a vertical sectional view of my improved wick carrying mechanism; Fig. 2 is an elevation of the wick, showing a carrier secured thereto; Fig. 3 is a section on line 3-3 of Fig. 1; Fig. 4 is a section on line 4-4 of Fig. 1; Fig. 5 is a section on line 5-5 of Fig. 1; Fig. 6 is 40 a side elevation of a modified form of exter-

nal perforated sleeve; Fig. 7 is a plan or edge view thereof; Fig. 8 is a side elevation of another modified form of external sleeve, and Fig. 9 is a plan or edge view thereof.

In carrying out my present invention, I 55 provide a perforated cylindrical sleeve 10, the perforations being utilized as means for raising and lowering the wick by a toothed wheel (not shown) in a manner well understood by those skilled in the art. The sleeve 60 may be transversely split, as at 11, and is preferably made of a suitable resilient metal, so that the edges 12 and 13 will spring together, and thereby hold the wick in position, when it is placed in the sleeve. 65

In order to hold the edges in accurate alignment a channel 14 may be struck outwardly and circumferentially around the body portion a short distance from the edge 12, as shown in Figs. 1 and 4. Projecting 70 outwardly from the edge 13 is a tongue 15, which fits into the channel 14, and by this means the sleeve may expand or contract and at the same time edges will be held in alignment. 75

To provide a convenient and adjustable mechanism for supporting the wick within the sleeve, the wick 16 may have permanently secured thereto, at its lower edge, a wick carrier 17, comprising a transversely split ring 80 provided with prongs 18, which are bent upwardly and imbedded into the outside of the wick, thus securing the wick and carrier together, and also providing a smooth metallic surface for guiding the wick and carrier into 85 the sleeve. The wick carrier is also provided with channel portions 19 projecting from the edge 20 of the ring, and which is adapted to engage a tongue 21, which projects from the edge 22, thus holding the edges in proper 90 alignment.

In place of using the tongue and channel described for properly maintaining the adjacent edges of the internal wick carrier or the external perforated sleeve in accurate 95 alignment, I may use other constructions, included within the scope of my invention. For instance, Figs. 6 and 7 shows the external perforated sleeve 10 provided with a tongue 30 made out of the material of the 100

sleeve and extending across the open area and projecting through a keeper 31 cut and pressed outwardly from metal of the sleeve adjacent the other edge. This makes a very simple construction and retains the edges of the sleeve against either inward or outward movement. I have shown this construction in Figs. 6 and 7 as applied to the external perforated sleeve. It is apparent however, 10 that the same characteristic may be embodied in the wick carrier.

Likewise both on the perforated sleeve and on the wick carrier, I may employ, if desired, interlocking positioning devices, as illustrated in Figs. 8 and 9. In that case, the sleeve (shown as the external sleeve) 10 has a tongue 35 projecting from one edge and acting between a pair of tongues 36 projecting from the other edge. These tongues are 20 made of the metal of the sleeve itself and are offset from the cylindrical surface so as to lie along the face adjacent the opposing edge, while the body of the sleeve remains in cylindrical registration.

25 It is to be understood that in use, the operation of the device is the same whichever form of carrier and sleeve construction, as above described, is used.

To hold the wick in position, the perforations in the sleeve 10 may be punched in such a manner that very small burrs 24 are left on the inside of the sleeve. These burrs engage the cotton wick and prevent any possibility of slipping. If desired, several of the 35 prongs 18 may be provided with prick punch burrs 23, which are positioned in such a manner that each will fit in a perforation of the sleeve. These burrs are small enough so as not to interfere with the teeth of the 40 raising wheel in the event that the wheels pass over one of the perforations into which a burr is projected.

In order to insert a new wick in the sleeve, it is only necessary to push the wick and the 45 wick carrier secured thereto downwardly into the sleeve until the bottom of the carrier is within the sleeve, as shown in Fig. 1, where it will be firmly held in place by reason of the burrs on the sleeve and on the wick carrier. Thereafter, the height of the wick is 50 adjusted by means of the ordinary toothed wheel mechanism.

When the wick has burned down to a point 55 where it can no longer be used, it is pulled upwardly within the sleeve and is held in its new position by the burrs on the wick carrier and sleeve. This operation may be repeated whenever necessary until practically all of the wick has been burned, when the 60 small remaining part of the wick and the carrier may be thrown away and a new wick and carrier inserted into the old sleeve.

From the foregoing description of a preferred form of my invention, it will be seen 65 that I have provided a simple wick carrying

mechanism, which can easily be adjusted and in which nearly all of the wick is used. It will also be seen that with my invention the same sleeve may be used repeatedly, and that a new sleeve need not be provided with each new wick, as is the present practice. Furthermore, by reason of the fact that the wick carrier and wick carrier sleeve are transversely split, the wick will be held firmly by the spring action of these members, and the members may be stamped out of a flat piece of metal, resulting in very economical manufacturing methods.

I claim:

1. In combination, a transversely split resilient sleeve, a wick-carrier, having a wick attached thereto, and cooperating means associated with said sleeve and wick carrier for adjustably securing said wick-carrier and wick within the sleeve. 80

2. In combination, a perforated cylindrical sleeve, a wick carrier comprising a split resilient ring adapted to have a wick attached thereto, and projections on said carrier adapted to engage the perforations of said sleeve and thereby hold the carrier and wick in position within the sleeve. 85

3. The combination of a tubular wick, a wick carrier comprising a split resilient cylinder adapted to be located principally within the wick while having at its lower end an up-turned portion to embrace the exterior of the wick, and a perforated sleeve surrounding the wick and carrier. 95

4. The combination of a tubular wick, a wick carrier adapted to be located principally within the wick while having at its lower end an up-turned portion to embrace the exterior of the wick, outwardly extending burrs on the up-turned portion of the carrier and a perforated sleeve surrounding the wick and carrier, the burrs on the carrier being adapted to cooperate with openings in the perforated sleeve. 100

5. The combination of a tubular wick, a wick carrier engaging the exterior and interior of the wick adjacent the lower end thereof, a split perforated sleeve surrounding the wick and carrier, a tongue carried by the perforated sleeve on its exterior extending beyond one edge thereof to coact with a retaining member on the sleeve adjacent the other edge thereof. 110

6. The combination of a tubular wick, a wick carrier comprising a split resilient cylinder adapted to be located principally within the wick while having at its lower end an up-turned portion to embrace the exterior of the wick, outwardly extending burrs on the up-turned portion of the carrier, and a split perforated sleeve surrounding the wick and carrier, the burrs on the carrier being adapted to cooperate with openings in the perforated sleeve, a tongue carried by the perforated sleeve on its exterior extending beyond 125

one edge thereof to coact with a channel on the sleeve adjacent the other edge.

7. In combination, a perforated sleeve having inward projections, a wick carrier having a tubular wick attached thereto and located within the sleeve, the projections cooperating with the wick to hold it in position.

8. In combination, a perforated cylindrical sleeve having inwardly projecting burrs formed by the punching of the holes, a wick carrier having a tubular wick attached thereto and located within the sleeve, the burrs cooperating with the wick to hold it in position.

15 9. In combination, a tubular wick, a perforated sleeve on the exterior of the wick, a wick carrier having a cylindrical sleeve on the interior of the wick, one of said sleeves having adjacent its edge a tongue projecting 20 across the other edge of the sleeve and the sleeve adjacent the other edge having an offset keeper constituting an integral strap displaced from the body of the sleeve to enable the tongue to be passed between the sleeve 25 proper and keeper.

10. In combination, a tubular wick, a carrier therefor having a sleeve on the interior of the wick, a perforated sleeve on the exterior of the wick, both of said sleeves being 30 split longitudinally and being provided with means to maintain registration adjacent the separation, said means comprising a tongue projecting from one edge of the sleeve overlapping the other portion of the sleeve beyond the separation, and a pair of tongues 35 on such other portion of the sleeve projecting from it on opposite sides of the first mentioned tongue and overlapping that portion of the sleeve carrying the first mentioned 40 tongue.

In testimony whereof, I hereunto affix my signature.

NATHAN F. FRETTER.
